D15-76.

OR D1,152

EX

Ms. 1152

James S. McCurdy, of Brooklyn, New York,
Assignor to J. M. Myers, of New York City,
Letters Patent No. 1152, Dated Oct. 4, 1850.

The schedule referred to in these Letters Patent, and making part of the same.

To all whom it may concern:

Be it known that I, James S. McCurdy, of Brooklyn, in the County of Kings and State of New York, have invented or produced a new and ornamental design for the Arms of Sewing Machines, and I do hereby declare that the following is a full and exact description of the same, reference being had to the annexed drawing, making part of this specification, in which

Fig: 1. is a side elevation, and

Fig: 2. is a plan of said arm.

The general design of the shape of said arm is that of a compound curve on one side rising from the point of attachment from the bed while the other

2

Ms. 1152

side is a nearly straight line ending in a semi-circular ornament:

Around the edge of this arm the otherwise flat sides are ornamented with a semi-circular bead or rib rendering such arms neat and pretty in the appearance of the design as represented in the drawing Figs. 1. & 2.

Having thus described and shown my said invention what I claim and desire to secure by Letters Patent is the ornamental Design of the Shape or configuration of the Sewing Machine arm as represented.

In witness whereof I have hereunto set my Signature this Thirty first day of August 1859.

Witnesses.
